UNITED STATES PATENT OFFICE.

MELLEN N. BRAY, OF BOSTON, MASSACHUSETTS, ASSIGNOR TO THE TUBULAR RIVET AND STUD COMPANY, OF MASSACHUSETTS.

SAMPLE ARTICLE.

SPECIFICATION forming part of Letters Patent No. 650,705, dated May 29, 1900.

Application filed March 5, 1900. Serial No. 7,389. (No model.)

To all whom it may concern:

Be it known that I, MELLEN N. BRAY, of Boston, county of Suffolk, and State of Massachusetts, have invented an Improvement in

5 Sample Articles, of which the following description, in connection with the accompanying drawings, is a specification, like letters on the drawings representing like parts.

The present invention relates to a sample 10 article and is shown as embodied in a sample rivet or stud, the object of the invention being to provide the article with means whereby it may be firmly secured to and combined with a card or mount, so that one or a group of 15 such articles may be conveniently preserved for inspection and reference. For this purpose the article in accordance with the invention is provided with a fastening or attaching device formed by abnormally cutting or 20 shaping a portion of the article itself without affecting the appearance of the article, as seen when it has been mounted, by attaching it to and combining it with the card or support.

25 It is to be understood that the term "abnormally" is intended to refer to the article as commonly used and not to the sample article, the abnormal condition of the one of course being the normal condition of the 30 other.

The invention is especially applicable to a tubular rivet or stud in which the fastening device may be easily formed by cutting and bending a portion of the shank of the rivet

35 to form an attaching-tongue without changing the appearance of the rivet, as seen when mounted, it being obvious, however, that the invention might be applied to other articles having similar or corresponding component 40 parts. In the case of the rivet or stud the flanged end contributes in holding the article in position on the mount, the said mount being notched or recessed to receive a portion of the flange of the rivet, so that the shank 45 will lie flat upon the face of the card or mount, while the fastening device, which has been formed by cutting and bending a portion of the said shank, may be engaged with the mount, so as to hold the stud securely thereon.

50 In the case of a card-mount the card is provided with a notch or slot to receive the flange

of the rivet, and the attaching-tongue of the shank is passed through the card and clenched on the other side.

Figure 1 is a plan view of a mount shown 55 as a card containing a series of sample rivets. Fig. 2 is a transverse section of the same on the line a^2 of Fig. 1, a portion of the rivet being shown in elevation.

The sample article a , which is herein shown 60 as a sample tubular rivet or stud, consists of the ordinary article, which has been abnormally cut or shaped to form a fastening device a^2 , adapted to serve as means for securing the article, when used as a sample, to a 65 card or mount b in any suitable way. As herein shown, the mount b is a piece of cardboard adapted to contain a line of tubular rivets displayed thereon. The said rivets are arranged to lie flat on the face of the card b , 70 which card is provided with openings or notches b^2 to receive portions of the flanges a^3 of the rivets, so that the shanks thereof will lie flat against the face of the card. The fastening device a^2 , which is shown as formed 75 by cutting a tongue from the wall of the shank, is bent away from the shank, passed through the card b , and clenched on the other side thereof, as best shown in Fig. 2. The sample articles are thus securely fastened 80 to the card by substantially-invisible fastening means, the appearance of each article for display purposes being unimpaired, although the articles have been rendered unfit for ordinary use.

85 While it may be stated that the invention has been successfully carried out with tubular rivets, it is not intended to limit the invention to these specific articles, since it is obvious that any article, a portion of which 90 may be abnormally cut or shaped without injuring the appearance of the article for display purposes, may be so cut to obtain a sample which can be secured to a card or mount in accordance with the invention.

95 I claim—

1. A sample consisting of an article having a portion abnormally cut or shaped to form a fastening device whereby said article may be secured to a card or mount for purposes of display.
2. A sample tubular rivet or stud which

consists of such a rivet or stud, the shank of which is abnormally formed to afford a fastening projection for the purpose of securing said rivet or stud to a card or mount.

- 5 3. The combination with a card or support provided with one or more notches or openings; of one or more tubular rivets or studs supported on said card, each with its shank parallel and adjacent to the surface thereof
10 and its flange or head projecting into the said opening, the said shank being abnormally cut

to afford a fastening projection, the said projection extending through the said card and being clenched on the opposite surface thereof, substantially as described.

In testimony whereof I have signed my name to this specification in the presence of two subscribing witnesses.

15 MELLEN N. BRAY.
